UNITED STATES PATENT OFFICE.

CHARLES HAMILTON PAJEAU, OF GLENCOE, ILLINOIS, ASSIGNOR TO THE TOY TINKERS, INC., OF EVANSTON, ILLINOIS, A CORPORATION OF ILLINOIS.

DESIGN FOR A JOINTED FIGURE TOY.

Application filed October 6, 1926. Serial No. 19,252. Term of patent 3½ years.

To all whom it may concern:

Be it known that I, CHARLES HAMILTON PAJEAU, a citizen of the United States, residing at Glencoe, in the county of Cook and State of Illinois, have invented a new, original, and ornamental Design for a Jointed Figure Toy, of which the following is a specification, reference being had to the ac-

companying drawings, forming part thereof.

The figure is a perspective view of a jointed figure toy, showing my new design.

I claim:

The ornamental design for a jointed figure toy, as shown.

CHARLES HAMILTON PAJEAU.
